CLAIM

The ornamental design for a lighting device, as shown and described.

DESCRIPTION

FIG. 1 is a left perspective view of a lighting device showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is an enlarged version of FIG. 6; and,

FIG. 9 is an enlarged version of FIG. 7.

The dashed broken lines in FIGS. 1-9 portions of the lighting device that form no part of the claimed design. The dashed-dotted broken lines in FIGS. 6-9 are for the purpose of annotating the enlarged views only and form no part of the claimed design.

1 Claim, 6 Drawing Sheets
